CLAIM

The ornamental design for a classification toy, as shown and described.

DESCRIPTION

FIG. 1 is a front perspective view of a first embodiment of a classification toy, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof of a second embodiment;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a front perspective view thereof of a third embodiment;

FIG. 18 is a rear perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof;

(Continued)

FIG. 25 is a front perspective view thereof of a fourth embodiment;

FIG. 26 is a rear perspective view thereof;

FIG. 27 is a front view thereof;

FIG. 28 is a rear view thereof;

FIG. 29 is a left side view thereof;

FIG. 30 is a right side view thereof;

FIG. 31 is a top view thereof;

FIG. 32 is a bottom view thereof;

FIG. 33 is a front perspective view thereof of a fifth embodiment;

FIG. 34 is a rear perspective view thereof;

FIG. 35 is a front view thereof;

FIG. 36 is a rear view thereof;

FIG. 37 is a left side view thereof;

FIG. 38 is a right side view thereof;

FIG. 39 is a top view thereof;

FIG. 40 is a bottom view thereof;

FIG. 41 is a front perspective view thereof of a sixth embodiment;

FIG. 42 is a rear perspective view thereof;

FIG. 43 is a front view thereof;

FIG. 44 is a rear view thereof;

FIG. 45 is a left side view thereof;

FIG. 46 is a right side view thereof;

FIG. 47 is a top view thereof; and,

FIG. 48 is a bottom view thereof.

The broken lines in the drawings illustrate the portions of the classification toy, which form no part of the claimed design.
